(57) **CLAIM**

The ornamental design for a soap dish radio, as shown and described.

DESCRIPTION

FIG. 1 is a top, front, and left side perspective view of a soap dish radio showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken-line disclosure in the views is for illustrative purposes only and forms no part of the claimed design.
